UNITED STATES PATENT OFFICE

WARNER I. CUBBERLEY, OF WASHINGTON, DISTRICT OF COLUMBIA

OFFICE ACCESSORY

Application filed August 1, 1929. Serial No. 382,742.

My present invention, in its broad aspect, has to do with improvements in supports, containers and filing devices for use in offices, shops, factories, libraries, and the like, and in part includes divisional subject matter contained in my co-pending application Serial #364,524, filed May 20th 1929, and which has matured into U. S. Patent No. 1,725,702. As described in my application referred to, 10 Serial #364,524, the solution of the problem of supporting objects in a vertical or substantially vertical position, resides in not only furnishing positive vertical support for such objects, such for instance as files, cards, manuscripts, magazines, folders, letters, books and the like, but also positively engaging said objects at their bottom edge in such a manner that they will not tend to slip down, bend, or slump down. My invention consists, 20 broadly, in providing in a single, unitary device both a vertical and horizontal support; that is, I provide a member bent intermediate its extremities to provide portions which are substantially at right-angles to each other; 25 one part constituting a vertical support, and the other part being ribbed, corrugated, up-struck, or provided with protrusions and constituting a horizontal support affording non-slipping contact with the object placed thereon through the instrumentality of the corrugations and the like. My invention is 30 designed to be used in units formed of two, three or more of said devices, same being interengaging and partially overlapping; the corrugations or the like of one device interengaging the corrugations or the like of the next adjacent device which may have its horizontal portion either extending in the same direction or reverted (as in the case of 40 book ends). More especially my device is designed to be used with filing cabinets, as a desk classifying set, as book ends, as a shop work bench accessory, to form compartments to hold tools, plans, papers, magazines and pamphlets and the like. The foregoing describes in part the subject matter of my copending application Serial #364,524. 45 My present application contemplates means whereby my units are threaded or carried on the rod of a base or support, which may be a file cabinet drawer, a mobile office or library unit, on a stationary support or the like. My device as constructed for use in this connection is shown in Figure 10 of my co-pending application Serial #364,524. That 55 is my present development includes some means other than the mere weight of the files, books or the like for holding the devices on a base. In libraries, offices, shops, factories and the like, it is oftentimes necessary and 60 desirable to transport books, files, plans, drawings and the like from place to place; for instance a clerk in charge of the mail will sort the mail, pull the correspondents' file wrappers, sort the mail and folders for 65 delivery to the proper officer to be attended to, and then place the sorted mail and folders in the several compartments or spaces formed by my devices on a mobile cart or stand; libraries on the other hand will use my device in lieu of the ordinary portable book tub; that is the books will be sorted out for 70 certain units of the book cases, so placed in the various compartments of a mobile unit of my devices and delivered to the proper shelves of the cases. In shops, work layouts, 75 plans, tools, instruments and accessories can be sorted out in one place and then delivered by a mobile unit of my devices to the various workmen, foremen, and the like. When used 80 in a file drawer my devices are carried on the usual rod that carries the tabbed spacer members, such as A B C D etc. spacers for the files, there being a tab similar to those of the followers for engagement with the rod 85 of the file drawer. In other words the means for retaining my members on a mobile unit is broadly similar to the usual rod construction 90 for a file cabinet drawer. 95

The broad adaptation of my present invention may therefore be defined in one aspect as including means whereby the elements defined in my co-pending application, Serial #364,524 are retained on a certain support by positive means.

While there has been described in the foregoing a number of objects and advantages of my present invention, others of equal importance will be apparent as the description

proceeds, the scope of the invention to be determined by the claims appended hereunto.

In the drawings wherein my invention is illustrated:—

5 Figure 1 is a perspective view of the same applied to a mobile cart or support formed of angle iron,

10 Figure 2 is a detail, perspective view of my device per se, and is broken away to show the locking tab,

15 Figure 3 is a detail perspective view of one end of the type of cart shown in Figure 1 and shows the manner of mounting the rod to hold my devices thereon, and the formation of the side runners or supports,

20 Figure 4 is a detail perspective view of the top of a leg and illustrated how it is attached to the top,

25 Figure 5 is a section showing the corrugated horizontal portion of an element and its relation to the upstanding side portion of a mobile cart or tray,

30 Figure 6 is a perspective view, broken away and in detail of the retaining rod and 25 its method of attachment to the mobile cart or tray,

35 Figure 7 is a modified form of my cart as shown in Figure 1, and in which the horizontal portions of the top, or the runners 30 extend almost to the rod so that the top of the cart forms a supporting base beneath my elements assembled thereon,

40 Figure 8 is an enlarged, detail, perspective view of one of my elements per se with the top or vertical portion reduced in height 35 compared to the length of the horizontal portion,

45 Figure 9 is a side view, partly in section, showing my device mounted, relatively interengaging, and carried on a mobile cart or tray formed of piping or tubing,

50 Figure 10 is a plan view of the blank from which my device is formed, and

55 Figure 11 is a modification showing how 45 certain forms of my devices may not only be interengaged, but may be interlocked.

60 In the drawings wherein like characters of reference are used to designate like or similar parts throughout the several views:—

65 My invention comprises a substantially rectangular section of sheet metal, or the like, bent between its ends to form a vertical portion (1) and a horizontal portion (2); the horizontal portions is slotted or formed with a gap (4) between the parts (3) and (5), and a tab (6) is struck down and formed with an opening therein (7); both portions or parts (3) and (5) are crimped, corrugated, or otherwise formed with protrusions or the like (8).

70 Conventional file cabinets, and the like, are formed with rods in their bottoms on which the spacer and alphabetical elements are carried. The gap (4) is designed to expose the rod with the parts (3) and (5) extending

75 to either side of the rod with the files, spacers and the like engaging in the corrugations (8) after the manner described in my pending application Serial #364,524; the vertical portions (1) of my devices supporting the files in vertical position, and the horizontal portions and corrugations preventing slipping or slumping down. My present devices are formed with the tabs (6) which also engage these rods through the openings (7) the rod extending through the opening.

80 In order that my device may be utilized in transporting books, tools, plans, files, pamphlets, and the like from place to place, to be used when and where desired; I have provided a mobile support or tray or cart, which is provided with a supporting structure A and a top C; the top has ends having upstanding parts 12 carrying the rod B on which my devices are threaded as shown in Figures 1 and 9. The supporting part A may have reinforcing bars G, and the rollers or casters D. Folders E, or books F, or any other objects are carried in the compartments formed by the vertical portions (1) on my devices; the horizontal portions of which overlap— 85 as shown in Figures 1 and 9—and prevents slipping or slumping down by means of the corrugations or ribs (8).

90 In the form of my cart or tray shown in Figure 1 I provide legs (9) formed of angle iron and L-shaped or angle iron side stringers (10) which have horizontal parts (10^a) forming tracks for my devices, and vertical parts (10^b) forming side guards and preventing my devices from becoming out of line. The end bars (11) have upstanding ears (12); the end bars being formed of ordinary strap iron; each formed with an opening (13) through which the rod B is 95 trained lengthwise of the cart, with its end screwthreaded and engaged in a fitting (14) internally threaded at (14^a) carried on the other end bar (13); there is a thumb nut or the like B' on the rod to screw it into place.

100 In practice my devices are placed on the cart with the horizontal portions partially overlapping and interengaging and carried in the side rails or stringers (10) in this position the tabs (6) extend down between the parts (10^a) of the side stringers with the openings (7) in line with the rod B; the rod is then threaded through the openings and screwed into place. My devices may be moved back and forth on the rod B, it being merely necessary to slightly lift up the corrugated horizontal portions, or slightly press the vertical portions in the direction of movement, to disengage the corrugations and move the device or devices to the new position or positions.

105 In attaching the legs (9) to the ends (11) and side stringers (10) one end of each leg is extended and bent over as at (9') and the device is assembled by first placing the end bars (13) and (11); then placing the side

stringers (10) and inserting the bolts or rivets or other securing means (15) in place to hold all the parts together. In the form shown in Figure 7 the parts (10^a) are extended toward each other—made of considerable width—to form a floor. If desired either or both of the side parts (10^b) may be extended in height either to form a backing for each compartment, or to form relatively high sides for a compartment between any two of the vertical portions. As shown in Figure 1 and in Figure 5 the side parts (10^b) are merely the height of the corrugations. In Figure 9 my tray or cart is shown as made up of piping or tubing, there being the usual castors D carried on the legs 9 and fittings carrying the top C which may be of wood or metal. In practice my devices may be so placed on the tray or in a file cabinet drawer that they partially overlap and interengage to form compartments in which files E, books F, or the like are carried, or if desired one or more, or all, may be placed so that they do not interengage; see the position of the device or element at the left-hand side of Figure 9.

In Figure 11 I have shown a modification in which the tab (6) is omitted; a pair of devices are assembled by placing the horizontal portions (2) at right angles to each other with the gaps in line; bringing them together so that the elements have an over-and-under relationship; then turning them so that horizontal parts (3) and (5) of one element respectively overlie and underlie parts (3) and (5) of the other element; view 1 shows their position to interlock them, and view 2 shows them locked together, in which position they may form book ends or the like.

Figure 10 illustrates the blank from which my devices are formed; the entire operation being performed by a single operation of a cutting and crimping die.

It is believed that the operation of my device is apparent from the foregoing, but attention is again called to its simplicity; its cheapness to manufacture; its practicability for the purposes accredited to it, and the fact that it is capable of a number of uses in and about an office, a shop, a library, in the home, and the like. Interpretation of the invention, however, should only be conclusive when made in the light of the subjoined claims.

55 I claim;

1. A support for vertical files comprising a body bent to provide a substantially vertical portion, and a horizontal portion, the horizontal portion provided with corrugations, a gap extending longitudinally of the horizontal portion, and an extension below and in line with the gap.

2. Interengaging members for supporting vertical files and the like, said members having partially overlapping horizontal por-

tions and relatively spaced apart substantially vertical portions, the horizontal portions being formed with corrugations which positively engage the bottom edges of objects placed thereon to prevent slipping, certain of the corrugations of each of the horizontal portions interengaging to hold the devices in certain positions relative to each other, and an extension on each of said members below the horizontal portions.

3. A device of the character described comprising a sheet metal body bent between its ends to form a substantially vertical portion and a horizontal portion, the horizontal portion being provided with spaced elevated portions arranged in series, and an extension on the body below the horizontal portion.

4. The combination with a base having a rod thereon, of a plurality of similarly formed members each having a substantially vertical portion and a horizontal portion, said horizontal portions positively interlocking and each having a longitudinal gap over the rod, and each member having an extension below the horizontal portion and in line with the gap and engaged by the rod to support said members on a base in cooperating relationship.

5. The combination with a base having a rod thereon, of a plurality of similarly formed members each having a substantially vertical portion and a horizontal portion, said horizontal portions being corrugated and each having a gap extending lengthwise thereof over the rod, said members adapted to be placed on the support with the horizontal portions partially overlapping and the corrugations interengaging, and each member having an extension below the horizontal portion and in line with the gap for slidably engagement by the rod to hold said members on the base in cooperating relationship.

6. A mobile supporting device for books, files and the like comprising legs and a top, the top having a rod extending lengthwise thereof, and side members constituting supports, a plurality of similarly formed members carried by the top and each having a horizontal portion and a vertical portion, the horizontal portions relatively interlocking and being seated on the side members, and each member having an extension below the horizontal portion slidably engaged by the rod to support the members on the top in relatively adjustable and cooperating relationship.

7. A mobile supporting device for books, files and the like comprising a wheeled base having a top formed with side stringers each having a horizontal and a vertical portion, a plurality of cooperating and similarly formed members on the top each having a horizontal portion carried on the side stringers and a substantially vertical portion ris-

- ing above the top, a rod carried by the top and extending lengthwise thereof below said members, and each of said members having an extension below its horizontal portion slidably engaging the rod to hold the members in place adjustably and in overlapping cooperating relationship with their horizontal portions interlocking to form a unitary continuous base.
8. A mobile supporting device comprising a wheeled base having a top and a detachable rod carried by the top and extending lengthwise thereof, a plurality of similarly formed members carried on the top and each having a corrugated horizontal portion and a substantially vertical portion; the horizontal portions partially overlapping with the corrugations interengaging, and each horizontal portion having a gap extending lengthwise thereof from end to end, and an extension on each member below the horizontal portion and in line with the gap and slidably engaging the rod to hold the members on the top in cooperating adjustable relationship for the purpose defined.
9. A mobile supporting device having a skeleton frame forming a wheeled base and a top having an opening between its sides and extending longitudinally thereof, a rod in the opening, and means slidable on the rod and having upstanding portions and positively interlocking horizontal foot portions for forming compartments the size of which may be independently adjusted by sliding said means on the rod toward and away from each other.
10. An office accessory for use with file supports of the type having a center rod for retaining the tabbed portions of file dividers and supports, a plurality of members each having a relatively horizontal portion formed with a center gap, and the horizontal portions arranged to either side and above the center rod and means fixing said horizontal portions in a permanent operative assembly to form a continuous base beneath the files.
11. An office accessory for use with file retaining devices of the type having a center rod for receiving thereon the tabbed portions of file dividers and supports, a plurality of members arranged in a normal substantially vertical operative position, horizontal portions connected with the vertical members and arranged to either side and above the center rod and provided with a gap above the center rod, and positively connected together to provide a unitary and continuous slotted base beneath the files.
60. In testimony whereof, I affix my signature hereunto.

WARNER I. CUBBERLEY.
